HUB CAP TOOL

Robert J. Irwin, 8653 Wabash, Seattle, Wash.

Filed Feb. 7, 1955, Ser. No. 486,374

1 Claim. (Cl. 29—245)

This invention relates to what will be designated as a "hub cap tool." More particularly it has reference to a tool designed to be used for the manual application and removal of hub caps from the wheels of present day automobiles.

It is the principal object of this invention to provide a tool of the above stated kind, by means of which hub caps of the large sizes, as presently being used on automobiles, can be easily and quickly removed from the wheels, and also may be easily and quickly applied without denting, scratching or in any way marring their surfaces.

It is a further object of the present invention to provide a tool of the above character that will accommodate the larger sizes of hub caps, in various diameters and forms, and which tool has a handle member that is common to both the cap removing and cap reseating elements thereof.

More specifically stated, it is the principal object of this invention to provide a tool of the above kind comprising an arcuate base bar, equipped with cushioning sleeves, adapted to be flatly engaged against the rim or peripheral portion of the cap for seating it, and from which bar a post extends outwardly to serve as a handle member that may be gripped in one hand for the purpose of holding the tool in proper position relative to the cap, and which post, at its outer end is equipped with a combined striking head and claw; the striking head being adapted to receive a blow thereagainst for the final seating of the hub cap after the tool has been properly placed thereagainst, and the claw being adapted to be used for the unseating or release of the cap from its holding clips, or from the wheel rim.

Further objects and advantages of the invention reside in the details of construction and combination of parts and in the mode of use of the tool, as will hereinafter be fully described.

In accomplishing these and other objects of invention, I have provided the improved details of construction, the preferred forms of which are illustrated in the accompanying drawings wherein:

Fig. 1 is a perspective view of the present tool as applied against a hub cap preparatory to its being seated and secured.

Fig. 2 is a plan or top view of the tool.

Fig. 3 is a cross section taken through the tool on the line 3—3 in Fig. 2.

Fig. 4 is a view illustrating the positioning and use of the tool for seating a hub cap on a wheel.

Fig. 5 is a view showing the manner of applying and use of the tool for the release of a hub cap from the wheel.

Explanatory to the present invention, it will here be noted that present day automobiles have their wheels equipped with relatively large hub caps of circular, dished, form; such caps generally being formed about their peripheral portions with concentrically arranged corruga-

2

tions, or valleys for both ornamental and functional purposes. Such hub caps are normally retained in place by the gripping action of a plurality of spring clips that are fixed to the peripheral portion of the hub cap to extend inwardly therefrom for engaging the tire carrying rim portion of the wheel. In the application, as well as in the removal of the hub caps, force must be applied to the cap to cause the clips to yield sufficiently that the cap can be driven into place. In the past, it has been a general practice in applying a hub cap to merely place it in position and then strike it a series of blows about its peripheral portion with the hand or a cushioned hammer, thus to force it into proper place. This procedure has quite frequently resulted in the cap being dented or otherwise marred. For the removal of the caps, it has been a practice to insert the end of a screw driver, or similar tool, between the wheel face and rim of the cap and then turn the screw driver in such manner as to pry the cap free from the wheel rim. This operation, also causes scratching or otherwise marring of the cap edge. It is to avoid such marring, denting or scratching of the caps in their application or removal that the present improved device has been designed.

Referring more in detail to the drawings:

The present tool comprises an arcuate bar 10, with a radius of curvature of about five and one-half to six inches, and extending through an arc of from 120° to 135°. Formed integral with the bar and extending outwardly therefrom at a point intermediate its ends, is a post 11 preferably having a length of about five inches. This is formed at its outer end with a flat and somewhat enlarged striking head 12, and extending from this, perpendicular to the post and in a direction outwardly from and radial of the bar, as seen in Figs. 2 and 3, is a prying tooth or claw 13. This tapers to its outer end and terminates in a sharpened edge, as seen at 14.

The bar 10 is round in cross section and about $5/8$ " in diameter. Fitted thereabout, adjacent its outer ends and near the post 11, are rubber cushioning sleeves 15, the purpose of which sleeve is to prevent any possible scratching of the hub cap surface by the application thereto of the tool in its use, and to cushion the blows applied against the head for the seating of the hub cap.

In use of the present tool, the post 11 serves as a handle member for the claw or tooth in the removal of the cap and also as a handle for the bar in its use for the reseating of the cap, as presently explained.

In the present specification, the term "hub cap" has reference to the smaller sizes of caps that are snapped over a plurality of spring clips on the wheel body, and also to the larger types herein illustrated which fill the space within the tire mounting rim, and which in trade are sometimes referred to as the "trim ring" or "trim disk." The latter types are provided adjacent the edge at one point with a hole for the passing of the valve stem outwardly therethrough.

For the applying or seating of a hub cap on a wheel, it is first placed properly in position for the passing of the valve stem through its peripheral opening, and is properly seated at that point. Then the tool is applied against a peripheral portion of the cap, for example as in Fig. 1, with the arcuate bar seated, if possible, in one of the concentric grooves or channels of the cap. When so seated, the tool is held in place by grasping the post portion 11 in one hand. Then, with the palm of the other hand, a sharp blow is struck against the head 12 thus to seat the spring clips as provided on that portion of the cap, within the wheel rim. This operation is repeated at different places progressively about the cap, and in this way it can be fully and effectively seated.

It is to be observed, particularly by reference to Fig. 3, that the post 11 leans inwardly toward the center of curvature of the bar 10. The reason for this is to cause the force of any blow struck against the head 12 in a cap seating operation to be distributed along the bar. By this distribution of force along the bar, there is no chance of the cap being dented as might be the case if the force of the blow is concentrated at a single point.

For the removal of a hub cap from a wheel, the tool is applied and used as has been illustrated in Fig. 5. This view shows a hub cap 20 as applied to a wheel and as equipped about the inside of its peripheral portion with spring clips, one of which is illustrated at 21. In applying the tool, it is grasped in one hand by the post or handle portion 11, and the sharpened edge of the tooth applied between the wheel rim and peripheral portion of the cap. Then by an upward pull on the handle, in the direction indicated by the arrow adjacent thereto, the rim of the cap can be pried free from the wheel at this point. This operation can be repeated at other places where holding is similarly effected.

It is to be understood that the arcuate bar 10 might be fitted to its full length, if desired, with the cushioning sleeves and it might be made longer or shorter and curved to a shorter or longer radius, without departing from the spirit of the invention. Also, it might be made of various materials or metals either as a single casting or as a tool fabricated from the several parts 10, 11, 12 and 13 separately formed and then joined in any suitable manner. At present, it is preferred to make the device of aluminum and as a single casting, and to apply

cushioning sleeves as herein illustrated. Also, to make it substantially in the dimensions previously given. However, it is not desired to in any way limit the device to specific dimensions, or materials.

One of the characterizing features of the invention resides in the fact that the present tool serves both the purpose of removing the cap and for replacing it, thus eliminating a two tool requirement.

Tools of this kind are easy to use, practical and entirely satisfactory in use and are relatively inexpensive.

Having thus described my invention, what I claim as new therein and desire to secure by Letters Patent is:

A hub cap tool of the character described comprising an arcuate bar adapted to be seated against the outer face of and along the peripheral portion of a hub cap for its application to a wheel, said bar extending through an arc of substantial extent, and a post fixed rigidly to said bar midway of its ends, to extend outwardly from the hub cap to which said bar may be applied and to lean toward the axial line of the wheel and an impact head at the outer end of the post.
